TANK CONSTRUCTION

Oscar Janssen, St. Louis, Mo., assignor to Oscar Janssen Stainless Steel Tanks, Inc., St. Louis, Mo., a corporation of Missouri

Application July 10, 1948, Serial No. 38,076

2 Claims. (Cl. 72—14)

1

This invention relates to tank construction, and more particularly to a construction for large-capacity concrete tanks having non-corrosive linings.

Among the several objects of the invention may be noted the provision of an economical construction for concrete tanks of relatively large capacity having a lining of non-corrosive metal keyed in the concrete; the provision of a tank construction of the class described wherein the lining economically may consist of light gage, non-corrosive sheet metal such as stainless steel; the provision of such a tank construction wherein the entire lining may be readily prefabricated, safely transported, and subsequently installed as a unit in the field; and the provision of a relatively large capacity tank of this class which is structurally strong, though devoid of internal bracing so that it may be readily cleaned. Other objects will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which one of various possible embodiments of the invention is illustrated,

Fig. 1 is a perspective of a multiple-tank installation embodying the tank construction of this invention, parts being broken away;

Fig. 2 is a side elevation of a vessel which forms a lining for a tank of this invention;

Fig. 3 is a plan view of the vessel of Fig. 2;

Fig. 4 is a front end view of the vessel of Figs. 2 and 3;

Fig. 5 is a perspective view of a welding jig employed in the fabrication of the vessel, the jig being shown as opened and having the bottom, top and side walls of the vessel in place therein for final assembly;

Fig. 6 is a perspective view of the interior of the front end wall of the vessel;

Fig. 7 is a perspective view of the interior of the rear end wall of the vessel;

Fig. 8 is a transverse section through the jig of Fig. 5, with the jig closed and rotated for down-hand welding of the top wall to a side wall;

Fig. 9 is a section similar to Fig. 8, illustrating the jig rotated to position the tank upright, and showing temporary internal bracing in the vessel; and,

2

Fig. 10 is a fragmentary detail perspective of a corner of a tank of Fig. 1, parts being broken away.

Similar reference characters indicate corresponding parts throughout the several views of the drawings.

Referring to the drawings, Fig. 1 illustrates a multiple-tank-installation 1, such as may be erected within a building 3 for containing wort during fermentation of beer for storage. The multiple-tank-installation 1 comprises a plurality of individual closed tanks arranged in horizontal rows and vertical tiers. Each tank per se comprises an elongate closed vessel 5 embedded in concrete 7. The concrete 7 is poured around all the vessels after they have been assembled in rows and tiers with adjacent vessels substantially spaced from one another, so as to form a plurality of tanks, each consisting of a concrete shell wherein a vessel is embedded with its walls forming a lining for the tank.

Each vessel, as more particularly illustrated in Figs. 2-4, is of generally rectangular cross section and comprises a bottom wall 9, vertical side walls 11 and 13, a top wall 15, and front and rear end walls 17 and 19, respectively. Each of these walls consists of an interior flat plate of light gage, non-corrosive sheet metal, such as stainless steel. Stainless steel plate of as light a gage as Number 18 U. S. standard gage, which is approximately .05" thick, may be used. The walls are welded together at their edges, as indicated at 21, to form a fluid-tight vessel.

The bottom wall 9, side walls 11 and 13, top wall 15, and end walls 17 and 19 are exteriorly reinforced and stiffened by means of corrugated plating 23, 25, 27, 29, 31 and 33, respectively, secured upon the outer faces of the walls. Thus, the interior of the vessel is unobstructed by any stiffening members and is wholly smooth. The corrugated plating is substantially coextensive in area with the corresponding wall of the vessel and may be secured by welding or in any other suitable way to the wall. The corrugated stiffener plates are formed of light gage sheet metal, which may be a relatively inexpensive sheet metal, but preferably is the same non-corrosive sheet metal as the walls of the vessel. The corrugations of the stiffener plates are preferably of substantially rectangular form. The corrugations of stiffener plates 23 and 29 for the bottom and top walls extend transversely with respect to the length of the vessel, and the

corrugations of stiffener plates 25, 27, 31 and 33

for the side walls 11 and 13 and end walls 17 and 19 extend vertically.

The front end wall 17 of the vessel is provided with a manhole for access to its interior and with a manhole cover 35. A sleeve 37 extends outward from the front end wall 17 surrounding the manhole so as to provide an opening through the concrete shell 7 for access to the manhole.

In constructing concrete tanks of this invention, or a multiple-tank installation such as illustrated in Fig. 1, it is highly economical to prefabricate the vessels 5 which are to form the linings for the tanks, rather than to assemble them in the field. Figs. 5-9 illustrate a method of prefabricating the vessels whereby they may be economically completed in the shop, ready for transport to and installation in the field, despite their relatively large size (of the order 42' x 10' x 10', for example).

As shown in Figs. 5-7, the bottom wall 9, the side walls 11 and 13, the top wall 15, and the end walls 17 and 19 are fabricated in the flat as individual units for ultimate assembly to form the vessel. The bottom wall is made up of a plurality of individual prefabricated panels 39. Each of these panels comprises a flat plate of elongate rectangular outline having a length corresponding to the width of the vessel and a width corresponding to a whole fraction of the length of the vessel. Spot welded to the flat plate of the panel is a corrugated stiffening plate, with the corrugations of the latter extending lengthwise of the flat plate so as to extend transversely in the completed vessel. The area of the corrugated plate projected upon the flat plate is substantially coextensive with the area of the flat plate so that the corrugated plate reinforces the flat plate substantially throughout the area of the flat plate. The panels are assembled side-by-side in the flat, and the flat plates of adjacent panels are welded together by continuous fluid-tight seams 41. This unites the flat plates of the panels to form the interior flat plate of the bottom wall with the exterior corrugated plates forming the stiffener plating 23 of the bottom wall. The top wall 15 is fabricated in the same manner, with panels 43 welded together by continuous fluid-tight seams 45.

The side walls 11 and 13 are fabricated in similar manner, wall 11 being shown to consist of panels 47 joined by continuous fluid-tight welds 49, and wall 13 to consist of panels 51 joined by welds 53. The interior plates of the panels of the side walls are preferably flanged at their ends, as indicated at 55, so that the side walls have continuous rounded flanges at their upper and lower edges. The front end wall 17 is fabricated on all four edges as indicated at 61. The rear end wall 19 is similarly fabricated of panels 63, joined by welds 65, and is also flanged on all four edges as indicated at 67. These flanges provide for easily cleaned rounded corners in the completed vessel.

The bottom, top, side and end walls thus formed are assembled by means of the jig of this invention illustrated in Figs. 5, 8 and 9. As shown, the jig consists of two separable jig sections, generally designated 69 and 71. The two jig sections are substantially identical, each comprising an elongate frame having a plurality of longitudinally spaced generally L-shaped frame plates 73 connected by longitudinal bars 75 and braced by transverse brace members 77. The frame plates 73 are formed with semi-circular outer peripheries so that they may be rotated

by rolling. One of the jig sections (the section 71 as shown in Figs. 5, 8 and 9) has its frame plates peripherally mounted on rollers 79.

For assembling a vessel 5, the two sections of the jig are separated and each section is set up with its frame plates in erect position, as illustrated in Fig. 5. The bottom wall 11 for the vessel is then placed in horizontal position, corrugated side down, upon the horizontal legs of the frame plates of the jig section 71, and is clamped in place by suitable clamps (not shown). Side wall 13 is placed in vertical position, corrugated side out, against the vertical legs of the frame plates of this jig section, with its lower edge abutting the adjacent edge of the bottom wall, and is clamped in place. The bottom wall 11 and side wall 13 are then welded together to form the continuous fluid-tight seam 21 for the corner of the vessel defined by these walls. It will be noted that this seam may be downhand welded.

The side wall 11 is placed in horizontal position, corrugated side down, upon the horizontal legs of the frame plates 73 of jig section 69, and is clamped in place. Top wall 15 is placed in vertical position, corrugated side out, against the vertical legs of the frame plates, with its lower edge abutting the adjacent edge of the side wall, and is clamped in place. The side wall 11 and the top wall 15 may then be downhand welded together to form the continuous fluid-tight seam 21 for the corner of the vessel defined by these walls.

The jig sections 69 and 71, with the side and top wall sub-assembly and the side and bottom wall sub-assembly therein, are then assembled by turning the section 69 clockwise through 90° from its Fig. 5 position and moving it into position for attachment to section 71 in such manner that the frame plates 73 of the two sections define complete circles for rolling purposes. This positions side wall 11 vertically with its lower edge abutting the free edge of the bottom wall 9, and positions top wall 15 horizontally with its free edge abutting the free upper edge of side wall 13. The jig sections may be held in their closed assembled relation by straps 81 bolted to the frame plates 73, or in any other suitable way.

The side wall 11 is then welded to the bottom wall 9 to form the continuous fluid-tight seam 21 for the corner of the vessel defined by these walls. This seam may be downhand welded. The entire jig is then rotated through 90° to the position illustrated in Fig. 8 to position the side wall 13 horizontally in the bottom of the jig, and the side wall 13 and top wall 15 then downhand welded together to form the continuous fluid-tight seam 21 for the respective corner of the vessel. The end walls 17 and 19 are then clamped in place and welded from the inside of the vessel to the end edges of the bottom, top and side walls by continuous fluid-tight seams, the jig being rotated as required to bring the joint being welded into position for downhand welding. Suitable inlet and outlet fittings such as indicated at 83 and 85 are welded in place. Suitable anchor members (not shown), preferably of stainless steel, for anchoring the vessel to the concrete may be welded to its exterior at a plurality of points.

After the vessel 5 has been thus fabricated in the jig and all its seams welded, it is tested for leakage while still in the jig by introducing air under pressure into the sealed vessel and applying a soap bubble solution along all the welded seams exteriorly of the vessel. If any leaks are found, the leaking seams are conveniently re-welded by turning the jig into position for down-

hand re-welding. The vessel may also be tested for leaks in the seams while still in the jig by brushing a mixture of a powdered fluorescent material and penetrating oil on a seam under test, then carefully wiping it off. If the seam is open, the penetrating oil carrying the fluorescent powder will reappear on the surface of the weld and may be detected by exposing the seam to a light that will cause the powder to fluoresce. This procedure for detecting leaks may also be used after the vessels have been encased in concrete.

A vessel for a tank of the capacity herein contemplated (tanks wherein the dimensions of the vessel are 42' x 10' x 10', for example) is not inherently structurally capable of withstanding the hydrostatic load of concrete poured there-around. The corrugated plating stiffens the walls of the vessel sufficiently to enable them readily to be handled in the course of prefabrication of the vessel, and usually sufficiently to withstand loads to which the vessel is subjected in being transported, but not sufficiently to withstand the pressure of poured concrete. Temporary bracing is therefore provided within the vessel particularly to enable it to withstand the hydrostatic load of concrete poured around the vessel. As shown in Fig. 9, temporary bracing 87 may be erected within the vessel while still in the jig, the latter being turned to bring the vessel into erect position. Access to the vessel for the erection of the bracing is had through the man-hole in the front end wall 17 of the vessel. This will enable the vessel not only to withstand the hydrostatic load of the poured concrete, but also better to withstand strains during transport. If strains encountered during transport are not severe, erection of the temporary bracing may take place in the field, before the concrete is poured.

The vessel 5 is then transported to the tank site and mounted in the desired position. Suitable formwork is built up around the vessel where necessary and concrete 7 is poured to form a shell of the desired thickness surrounding the vessel. The concrete is preferably poured in successive steps, rather than to the full height of the vessel in one pouring, to reduce the hydrostatic pressure on the vessel and its temporary internal bracing. The vessel is keyed within the shell by the concrete between the corrugations of the plating, which also forms concrete ribs for additional stiffening of the tank to enable it to resist internal pressure. Concrete also enters the corrugations through their open ends and keys the walls of the vessel to the concrete shell. In this respect, it will be observed that the corrugations are of substantial width and depth and their length is slightly less than the respective walls of the vessel so that the ends of the corrugations are spaced from the corner seams and open at said ends. When the concrete has set and is self-sustaining, access to the interior of the tank is had through the manhole in the front end wall to disassemble the bracing 87 and remove it. It will be understood that suitable reinforcement for the concrete may be provided.

An important feature of the invention resides in the elimination of a very substantial proportion of the relatively costly formwork ordinarily required for pouring concrete vessels. This is because in a multiple-tank installation such as illustrated in Fig. 1, for example, the walls of the vessels forming the tank linings serve to a considerable extent as forms for the concrete.

The only formwork required is at the ends of the tanks and at the sides of the tanks at the ends of each tier of tanks. If two rows of tanks are provided in each tier, with the rear walls of the vessels in the two rows back-to-back, then the rear walls of the vessels serve as forms for the concrete poured between the rear walls. The elimination of any necessity for a large proportion of formwork constitutes a cost saving justifying the use of the relatively expensive stainless steel tank linings.

The tank construction of this invention thus economically permits the use of relatively expensive non-corrosive sheet metal such as stainless steel, since light gage material may be used with the resultant saving in the amount of such material. Economy also results from the prefabrication of the vessels 5 which form the tank linings, prefabrication being more economical than assembly of the vessels in the field. No permanent internal bracing is required, and the tank interior may therefore be readily cleaned.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

1. A tank having a lining consisting of an elongate vessel of generally rectangular cross section having flat bottom, side, top and end walls, each of said bottom, side and top walls consisting of a plurality of panels extending transversely with respect to the length of the vessel, each panel comprising an interior flat sheet metal plate extending the width of its respective wall and a fraction of the length of its respective wall and an exterior corrugated sheet metal plate welded to the flat plate with its corrugations extending transversely with respect to the length of the vessel, the area of the corrugated plate projected upon the flat plate being substantially coextensive with the area of the flat plate so that the corrugated plate reinforces the flat plate substantially throughout the area of the flat plate, the flat plates of adjacent panels in each of said bottom, side and top walls being welded together by continuous fluid-tight transverse seams, the bottom, side and top walls also being welded together by continuous, fluid-tight corner seams extending longitudinally the full length of the vessel, the corrugations of the corrugated plating being of substantial width and depth and their length being slightly less than the width of the respective walls of the vessel so that the ends of the corrugations are spaced from the corner seams, and the corrugations being open at their said ends adjacent said corner seams, each of the said end walls also consisting of a plurality of panels, each of which comprises an interior flat sheet metal plate and an exterior corrugated sheet metal plate welded to the flat plate, with the area of the corrugated plate projected upon the flat plate substantially coextensive with the area of the flat plate and having the corrugations open at its ends, the flat plates of adjacent end wall panels being welded together by continuous fluid-tight seams, and the end walls being welded at their edges to the bottom, side and top walls by continuous fluid-tight seams, and a shell of concrete embedding the vessel adapted to with-

stand the load due to the pressure of the contents of the tank, the concrete between the corrugations of the corrugated plates forming stiffening and keying ribs and concrete entering the corrugations through their open ends keying the walls of the vessel to the shell.

2. A tank as set forth in claim 1 wherein each end wall panel extends the height of the end wall and a fraction of its width, and the corrugations extend vertically.

OSCAR JANSSEN.
